UNITED STATES PATENT OFFICE.

RUDOLPH G. SEGGSCHNEIDER, OF WEST ORANGE, NEW JERSEY.

MACHINE FOR FORMING WELTS ON HAT BRIMS.

Application filed November 18, 1922. Serial No. 601,676.

To all whom it may concern:

Be it known that I, RUDOLPH G. SEGGSCHNEIDER, a citizen of the United States, and a resident of West Orange, county of 5 Essex and State of New Jersey, have invented certain new and useful Improvements in Machines for Forming Welts on Hat Brims, of which the following is a specification.

10 This invention has for its object to provide a machine for turning over and ironing down the edge of a hat brim so that a welt is formed, which welt is usually stitched down after the hat leaves the machine.

15 The invention relates to a machine of this kind which feeds the hat around and also folds and presses it while it rotates, and one in which the folded over part is made to lie against either the top or the 20 bottom face of the brim.

25 The machine which is the embodiment of this invention is adjustable to vary the width of the folded over portion or welt, and is also adapted to permit easy and quick insertion or removal of a hat in and from the machine.

30 The invention is illustrated in the accompanying drawings, in which Figure 1 is a top view of a machine embodying my invention. Figure 2 is a section on line 2-2 in Figure 1. Figure 3 shows part of a hat brim folded over at its edge. Figure 4 is a detail of the folding means open to permit the insertion or removal of a hat brim. 35 Figure 5 is a bottom view of the machine shown in Figure 1. Figure 6 is a front view of the machine with the table in section. Figure 7 is a view of the folding means engaging the hat brim. Figure 8 is a detail section showing the iron and the feed roller engaging a hat brim to fold the welt on top of the hat brim, and Figure 9 is a detail showing a folded brim as folded by the mechanism in Figure 8.

40 In this machine as illustrated the table portion 10 is made substantially flat so as to support the hat 11 so that the hat can be rotated on the table, the machine being provided with a driving shaft 12 which can be suitably driven, as by means of the belt 13 passing over the pulley 14.

45 Projecting up through the table is a feed roller 15 mounted on a shaft 16 and driven from the shaft 12 by a suitable connection, and in the drawing I show a worm 17 on the shaft 12 which is in mesh with the worm

50 gear 18 on the shaft 16. The top of the feed roller 15 is substantially flush with or can be raised slightly above the top face of the table 10 so that it can grip the brim 19 of the hat.

Above the feed roller is an iron 20 which is substantially smooth on its bottom face and can be suitably heated, as by a gas flame projected by the pipe 21 on the back of the iron, so that the flame enters the chamber 22 and the heat is thus confined sufficiently to fully heat the iron 20. The iron 20 is mounted so that it can be removed from contact with the hat brim when there is no feeding 55 and to permit insertion and removal of the hat brim, and in the form shown the iron is mounted on a spring 23 fastened at its back end to the table and at its front end to the iron, and an adjustable screw 24 is 60 preferably provided to limit the downward movement of the iron, the function of the spring 23 being to normally press the iron upward.

To press the iron downward I arranged 65 a shaft 25, the portion opposite the spring or iron being off-set, as at 26, to provide a cam action when the shaft 25 is rotated in its bearings 27 by means of the handle 28. It will also be evident that, when turned 70 downward, as shown in Figure 2, this off-set or cam-like portion of the shaft 25 locks the iron down.

Situated so as to receive the hat brim after it leaves the iron, and to keep it pressed 75 down while it is becoming cool, I provide a presser plate 29 which is connected with the table as by means of the strip 30, and is elevated from the table sufficiently to receive the hat brim after it is folded over 80 to form the welt, and thus hold the welt down in its ironed position until it becomes 85 set and more cool.

The folding means is placed adjacent to the iron and comprises an abutment member 100 31, against which the edge of the hat brim is designed to abut and to be folded over thereby, since the outer face of the abutment member shown at 32 is recessed with an over-hanging shelf-like portion 33 at the 105 top thereof so as to curl the brim over as it is fed through the machine.

When the hat is started, the welt is turned 110 over the required distance and inserted in the folding means, and then the pivoted plate 34 is swung down, this plate being pivoted at 35, and the curled end 36 of the

plate enters between the welt and the main brim portion so as to hold these parts separated until they enter the ironing and pressing means, and also to form a guide to regulate the width of the portion folded over; in other words, to regulate the width of the welt.

The abutment member 31 is fixed, but the part to which the plate 34 is hinged is adjustable, in the form shown this being by means of a strip 37 resting on the table and adjustable thereon and adapted to be held in its adjusted positions. To secure this adjustment I show in the drawing a slot 38 in the strip 37, and a set-screw 39, by means of which it can be adjusted, and a suitable scale 40 can be placed at the proper point to define the width of the welt. The over-hanging part 36 of the plate 34 is curled and inclines inward relative to the curved shelf 33 and the curved recessed part 32 of the abutment member 31.

This construction, it will be evident, forces the hat brim over into a curled part as it enters the folding means, until the curled over edge of the brim engages the inner face of the part 36, and it is then limited, and in this way the width of the fold is determined. After this width of fold is folded over to form the welt it passes directly from the folding means to the iron, being propelled across the under face of the hot iron by the feeding roller 15. The hat is free to revolve on the flat table, and it therefore passes around until all parts of the brim have been folded.

When it is desired to remove the hat the handle 28 is turned, and this, through the shaft 25, releases the iron and the spring 23 raises the iron up, and then the folding plate 34 is swung upward. This removes its curled end 36 from between the folded portions of the hat brim, and the hat can then be removed without materially distorting or unfolding the welt.

The plate 34 can be held in its raised and lowered positions, and I show for this purpose, in the drawing, a spring 41 which bears against the handle 42 of the folding plate,

and, resting in any of the notches 43, holds the plate in its adjusted position either closed or open.

The normal way to form the welt is to fold the material from the edge over on the top face of the brim. If, however, it is desired to place the welt on the bottom face of the brim, as shown in Figure 9, the hat can be inserted upside down in the machine, and for this purpose I provide a cover 44 which is readily removable, and it can be attached to the table by suitable means, such as screws 45, and when these are removed the cover 44 can be removed and the hat then laid on the table with only its brim supporting it, the crown portion extending downward through the opening provided when the cover 44 is removed. This inverted position of the hat will be readily understood from Figure 8.

I claim:

1. A machine for forming welts on hat brims comprising a table, a feed roller extending through the table, an iron supported above the feed roller, the iron being mounted on a spring arm, a rod with a projecting part to force the iron toward the roller, and a screw on the spring arm adapted to engage the table, thus forming an adjustable means for limiting the movement of the iron toward the roller.

2. A machine for forming welts on hat brims comprising a hat support on which the hat brim rests and rotates, a feed roller projecting through said support, a stationary iron above the roller and normally removed out of feeding relation therewith, a manually operable means for forcing and holding said iron in feeding relation with the roller, an adjustable abutment member adjacent the iron, and a pivoted fold-engaging plate on said member, a notched handle on the plate, and a spring on the member to engage the notches to hold the plate in its adjusted positions.

In testimony that I claim the foregoing, I have hereto set my hand, this 17th day of November, 1922.

RUDOLPH G. SEGSCHNEIDER.
